UNITED STATES PATENT OFFICE.

WILLIAM DAVIS HOOKER, OF CHICAGO, ILLINOIS.

DIRECT-ACTING ENGINE.

SPECIFICATION forming part of Letters Patent No. 585,630, dated June 29, 1897.

Application filed November 19, 1896. Serial No. 612,779. (No model.)

To all whom it may concern:

Be it known that I, WILLIAM DAVIS HOOKER, a citizen of the United States, residing at Chicago, in the county of Cook and State of Illinois, have invented a new and useful Improvement in Direct-Acting Steam-Engines, of which the following is a specification.

My invention relates to improvements in direct-acting steam-engines in which the main valve is driven and arrested by steam. The essential features of the mechanism which I employ in the present invention are found in a patent granted to me for improvements in direct-acting steam-engines dated December 6, 1870, No. 109,904, in which puppet-valves are shown in supplemental piston to admit live steam to drive the supplemental piston and with it the main valve of the engine and arresting and cushioning it on the exhaust steam or atmospheric pressure; also, patent granted to me for improvements in direct-acting steam-engines dated July 16, 1872, No. 129,345, in which ports in the supplemental piston and ports in said piston valve chest are so arranged that live steam will be supplied through these ports when the piston is near the end of its strokes to arrest and cushion the piston on compressed live steam; and the object of my present invention is to so combine these inventions in one engine that the supplemental piston and with it the main valve shall be driven by live steam supplied by both the supplemental valve and supplemental piston, the supplemental piston supplying live steam from the valve-chest to arrest the said piston on compressed live steam, thereby getting a quick motion of the said piston and a powerful steam-cushion to positively prevent it from striking its cylinder-heads.

Referring to the accompanying drawings, similar letters indicate like parts which I consider the best means for carrying the invention into practice.

Figure 1 is a longitudinal vertical section taken on line $a-a'$. Fig. 2 is an end elevation of the engine and valve-chest.

A represents a steam-cylinder; B, a piston therein; C, the piston-rod; D, the main valve

for controlling the admission of steam to and 50 its exhaust from the steam-cylinder; E, the valve-chest of engine; F, the supplemental piston; $g g'$, puppet-valves in the ends of said piston to close ports $h h'$ to cushion the supplemental piston on compressed live steam 55 when the ports $h h'$ are covered by puppet-valves $g g'$; $i i'$, ports in supplemental piston, through which live steam from the steam-chest is admitted to ports $j j'$, leading to the 60 ends of steam-chest after the puppet-valves $g g'$ have closed the ports $h h'$ just before the piston reaches the cylinder-heads $G G'$, thereby arresting the said piston on compressed live steam, and there will be no danger of the 65 piston striking the valve-chest heads, which often occurs when the puppet-valves $g g'$ only are employed, as shown in my patent of December 6, 1870. When, as in my patent of July 16, 1872, the ports $i i'$ in supplemental piston and ports $j j'$ in valve-chamber only 70 are employed, if the piston were at or near the cylinder-heads the live steam supplied by the supplemental valve H through ports $h h'$ could not get behind the ends of supplemental piston to start it, as, the ports $j j'$ being 75 covered by the supplemental piston, the said piston would start slowly or not at all; but when both the puppet-valves $g g'$ in supplemental piston F are used, together with the ports $i i'$ in said piston and ports $j j'$ in 80 valve-chest E, live steam controlled by the supplemental valve will pass by the puppet-valves $g g'$ and behind the ends of supplemental piston F, giving the full power of the steam to drive the piston. As the puppet-valves close the exhaust-ports $h h'$, the live 85 steam from the steam-chest will be supplied through ports $i i'$ and $j j'$ behind the ends of the piston F, and then, the ports $i i'$ passing over and closing ports $j j'$, the live steam will 90 be confined between the ends of the supplemental piston and valve-chest heads and the piston will be arrested on compressed live steam. I is the supplemental-valve chest, and J, the supplemental-valve rod. This supplemental valve H may be connected to the main piston B by any suitable valve movement so 95 arranged as to reverse the valve H when the

main piston is near the termination of its strokes.

What I claim, and desire to secure by Letters Patent, is—

- 5 The combination with the supplemental piston F, having puppet-valves g , g' , ports h , h' , supplemental valve H, of the ports i , i' , in supplemental piston F, and ports j , j' , in

valve-chest E, and a valve-movement connecting the main piston to valve H, substantially as described and for the purpose set forth.

WILLIAM DAVIS HOOKER.
